CLAIM

The ornamental design for a fishing lure body, substantially as shown and described.

DESCRIPTION

FIG. 1 is a side elevational view of a fishing lure body showing my new design, the opposite side thereof being a mirror image thereof.

FIG. 2 is a top plan view thereof.

FIG. 3 is a bottom plan view thereof.

FIG. 4 is a front elevational view thereof as seen from the left side.

FIG. 5 is a rear elevational view thereof as seen from the right side of FIG. 1.

Components shown in broken lines do not form a part of my new design for a fishing lure body, but are illustrated to show utilization thereof in a complete lure.
